(57) **CLAIM**

The ornamental design for an insect bait device, as shown and described.

DESCRIPTION

FIG. 1 is top, front perspective view of a first embodiment of an insect bait device according to the new design, the portion shown in broken lines forming no part of the claimed design;

FIG. 2 is a front elevation view of the embodiment of FIG. 1;

FIG. 3 is a back elevation view of the embodiment of FIG. 1;

FIG. 4 is a top plan view of the embodiment of FIG. 1;

FIG. 5 is a bottom plan view of the embodiment of FIG. 1;

FIG. 6 is a left side elevation view of the embodiment of FIG. 1;

FIG. 7 is a right side elevation view of the embodiment of FIG. 1;

FIG. 8 is a back, bottom perspective view of the embodiment of FIG. 1;

FIG. 9 is top, front perspective view of a second embodiment of an insect bait device according to the new design, the portion shown in broken lines forming no part of the claimed design;

FIG. 10 is a front elevation view of the embodiment of FIG. 9;

FIG. 11 is a back elevation view of the embodiment of FIG. 9;

FIG. 12 is a top plan view of the embodiment of FIG. 9;

FIG. 13 is a bottom plan view of the embodiment of FIG. 9;

FIG. 14 is a left side elevation view of the embodiment of FIG. 9;

FIG. 15 is a right side elevation view of the embodiment of FIG. 9;

FIG. 16 is a back, bottom perspective view of the embodiment of FIG. 9;

FIG. 17 is top, front perspective view of a third embodiment of an insect bait device according to the new design, the portion shown in broken lines forming no part of the claimed design, the dashed lines showing indeterminate length;

(Continued)

FIG. 18 is a front elevation view of the embodiment of FIG. 17;
 FIG. 19 is a back elevation view of the embodiment of FIG. 17;
 FIG. 20 is a top plan view of the embodiment of FIG. 17;
 FIG. 21 is a bottom plan view of the embodiment of FIG. 17;
 FIG. 22 is a left side elevation view of the embodiment of FIG. 17;
 FIG. 23 is a right side elevation view of the embodiment of FIG. 17; and,
 FIG. 24 is a back, bottom perspective view of the embodiment of FIG. 17.
